BICYCLE MIRROR

Emil Kirwin, Holywood, Fla., and Jack Kramer, Bronx, N.Y., assignors to D. P. Harris Hardware & Manufacturing Co., Inc., New York, N.Y.

Filed Nov. 23, 1970, Ser. No. 26,114

Term of patent 14 years

Int. Cl. D12—16
U.S. Cl. D90—1

FIG. 1 is an elevational view of a bicycle mirror showing our new design;

FIG. 2 is a right side view thereof;

FIG. 3 is a left side view thereof;

FIG. 4 is a top plan view thereof;

FIG. 5 is a rear elevational view thereof; and

FIG. 6 is a rear perspective view thereof, on a reduced scale.

The broken line representation of a bicycle in FIG. 6 is for purposes of illustration only.

We claim:

The ornamental design for a bicycle mirror, substantially as shown and described.
